United States Patent Office.

WALTER A. LOVELACE, OF RICHMOND, MASSACHUSETTS.

Letters Patent No. 94,902, dated September 14, 1869.

IMPROVED INTERFERING-PAD.

The Schedule referred to in these Letters Patent and making part of the same.

To all whom it may concern:

Be it known that I, WALTER A. LOVELACE, of Richmond, in the county of Berkshire, and State of Massachusetts, have invented a new and improved "Interfering-Pad," and I do hereby declare that the following is a full, clear, and exact description of the same, reference being had to the accompanying drawings, which form part of this specification.

The difficulties heretofore attending the use of interfering-pads have been, first, that on account of the unyielding or non-elastic nature of the pad-fastenings, and the attendant variation in the circumference of the horse's leg, owing to the distension or relaxation of the muscles thereof, the apparatus must, of necessity, either bind the leg too tightly while the muscles are distended, as, for instance, when the leg is sustaining the weight of the body, or else must fit too loosely while the muscles are more relaxed, as, for example, when the leg is lifted from the ground—in the former case inflicting not only pain, but also injury to the horse, and in the latter case allowing of the easy disarrangement of the pad from slight causes; secondly, that the formation of the said fastenings, or straps, being necessarily broad, for avoiding, as much as possible, their cutting into the muscles while distended, gravel and other granular substances are sometimes lodged between them and the leg, while the pad is fitting loosely, and are subsequently embedded in the muscles when they are again distended.

The principal object of my invention is to obviate these difficulties, and thereby remedy their attendant evils; and to this end,

The apparatus consists of an interfering-pad, constructed or provided with wire or elastic metal-clamps, whereby the end is attained.

The invention also consists in the combination with the above of a pad or pad-frame, constructed of elastic wire, in a convolute form, whereby a better protection is afforded and a more durable apparatus is obtained.

Referring to the accompanying drawings—

Figure 1 represents a perspective view of an interfering-pad, constructed according to my invention; and

Figures 2, 3, and 4 represent perspective views of interfering-pads provided with my elastic-wire clamp,

illustrating its applicability to pads for protecting different parts of the leg.

Similar letters of reference indicate corresponding parts in the several drawings.

A is an interfering-pad of the ordinary construction.

To this pad A is attached my elastic-wire clamps B, in a manner as shown, so that by their elasticity, provision is made for a close but easy fit in the different positions of the leg, and under different conditions of the muscles thereof. These clamps B are constructed of a single piece of wire, and are so formed as, in their normal state, to fit, as nearly as is practicable, the transverse form of that portion of the leg upon which they are designed to rest.

For securing the apparatus to the leg, after being placed thereon, the extremities of the clamp are connected with each other by means of a leather strap, a, which, being secured in a loop, or ring on one end, is passed over a hook on the other.

Additional elasticity may, when desirable, be given to the clamps, by forming in the wire, at suitable localities, spring coils b, as represented.

A' is an elastic-wire pad, or pad-frame, which may be used, in combination with the elastic clamps B, with or without the usual leather pad A. Said wire pad, or pad-frame A', is constructed in one piece with the clamps, and in a convolute form, as shown in fig. 1. It is designed to serve the same purpose as the leather pad A, when used alone, and when used in connection therewith it may, by recurring the blows from the interfering hoof, not only add to the protection of the part struck, but also to the durability of the pad.

I do not claim an elastic strap or band; but

What I claim as my invention, and desire to have secured by Letters Patent, is—

1. An interfering-pad, provided with wire or elastic-metal clamps, constructed substantially as shown and described.

2. In combination with the elastic-metal clamps, the pad, or pad-frame, constructed of elastic wire, in a convolute form, substantially as specified.

WALTER A. LOVELACE.
